CONTROL MECHANISM FOR CONCRETE
MIXERSAndrew McMillan, Milwaukee, Wis., assignor to
Chain Belt Company, Milwaukee, Wis., a cor-
poration of Wisconsin

Application February 15, 1944, Serial No. 522,479

8 Claims. (Cl. 74—53)

The invention relates to concrete mixers and has for one of its objects the provision of an improved mechanism for controlling certain of the instrumentalities thereof. For purposes of disclosure it will be here described as applied to control of the discharge chute of a concrete mixer of the so-called "paving type."

Such machines commonly include a rotatable mixing drum having an opening in one end wall through which the mixed concrete is discharged at the conclusion of the mixing cycle, such discharge being effected through movement of a discharge chute from a normally inoperative position to one in which it intercepts or receives the mixture being agitated within the drum, and conveys it through the said drum opening. The movements of the chute to and from discharging position may be effected manually, but more frequently the chutes are moved by power derived from the power plant of the mixer, through mechanism such, for example, as that disclosed in U. S. Patent No. 1,415,411, granted May 9, 1922, on an application filed by Samuel Shafer, Jr.

In the application here disclosed, the present invention is illustrated as controlling one of these "power discharge" mechanisms, and the control, while manually actuated by the operator with a minimum of effort, actually effects setting of the power discharge device into operation by means of power derived from the mixer power plant. Since operation of the discharge chute is but one of several duties of the operator, and since under present day practice it must be performed each 40 to 70 seconds, the "fingertip" control thus provided results in an appreciable reduction in the physical effort required and thereby lessens fatigue of the operator.

It is also common practice to provide mixers of the paving as well as of other well known types with timing devices, known as batch meters, which are set into operation at the beginning of the mixing period and after a predetermined time give a suitable signal or indication whereby the operator may know that the batch is completely mixed and ready for discharge. Frequently interlocks have been provided between the batch meter and the discharge chute actuating mechanism, whereby it has been impossible to move the discharge chute into the drum to effect discharge of the batch until the batch meter has given its signal that the mixing period has been completed.

The present invention includes an improved and simplified form of such interlocking mechanism, which furthermore is arranged to unlock

the power discharge device slightly in advance of the termination of the mixing period as determined by the batch meter, whereby any lag between the completion of mixing and the beginning of discharge of the mixed batch may be eliminated. That is to say, ordinarily it may take an appreciable period of time for the operator to react at the end of the mixing cycle and put the power discharge mechanism into operation and thereafter several seconds to move the discharge chute from its normal inoperative position outside the drum to its discharging position within the drum, and if the discharge mechanism is kept locked until the batch meter signals the expiration of the full mixing period, even if the operator starts the power discharge mechanism immediately upon receiving the batch meter signal, several seconds will necessarily elapse before the discharge chute will have been moved sufficiently to start discharge. The present interlock is so arranged however, as to unlock the power discharge control adequately before the batch meter signal so that by the time such signal is given the discharge chute may have at least partially completed its movement from non-discharging to discharging position.

One form of apparatus constructed and arranged in accordance with the invention is illustrated in the accompanying drawings forming 30 a part of this specification, in which like reference characters designate like parts in all the views, and in which:

Figure 1 is a fragmentary side elevational view, partly broken away and in section, illustrating such elements of a well known example of a paving mixer as are essential to an understanding of the invention, with power discharge control and interlocking mechanism constructed and arranged in accordance with the invention incorporated therein;

Fig. 2 is an enlarged sectional-elevational view, taken approximately on the plane indicated by the line 2—2 of Fig. 1, looking in the direction of the arrows, showing the mechanism for effecting actuation of the starting lever of a conventional power discharge mechanism through power derived from the power plant of the mixer;

Fig. 3 is a sectional-elevational view of the parts illustrated in Fig. 2, as seen from the left thereof;

Fig. 4 is a top plan view of the parts shown in Fig. 2; and

Figs. 5 and 6 are views, largely diagrammatic, illustrating the interlocking mechanism between the batch meter and the power discharge control

mechanism, and showing various positions assumed by the parts in a cycle of operation.

Referring more particularly to Fig. 1, the conventional concrete mixer elements shown comprise a framework 10 mounted for ground traverse upon crawler treads 11 and having a mixing drum 12 rotatably mounted within it upon rollers 13. Said drum is driven by a chain and sprocket drive 14 from a countershaft 15 which, during operation of the machine, is constantly driven from the power plant of the mixer (not shown). A discharge chute 16 is pivotally mounted on the framework 10, as at 17, and is adapted to be swung from its inoperative position (shown in Fig. 1) through the discharge opening provided in the rear end wall 18 of the drum 12, to a reversely inclined operative position, at least partially within said drum. This movement of the chute, as well as reverse movement to withdraw it from the drum at the completion of discharge, is accomplished through an arm 20 carried by the shaft 17, a link 21, a bell crank lever 22 and a link 23 which is connected to the crank arm 24 of a power discharge device 25, which may be of the type disclosed in the above mentioned Shafer Patent No. 1,415,411. This device may be driven from the countershaft 15 by a chain and sprocket drive 26, and is provided with a lever 27 by means of which it may be thrown into operation.

A batch meter 28 is also provided, for timing the mixing period and giving a signal at the conclusion thereof, usually an audible one by means of a bell 29.

The control mechanism of the present invention, for actuating the starting lever 27 of the power discharge device 25, is best shown in Figs. 2, 3 and 4, and comprises a supporting bracket 30 mounted upon a member 10' of the mixer framework. The said bracket carries a bearing sleeve 31 in which is journalled a rock shaft 32 provided at one end with a crank arm 33 carrying a crank pin 34 upon which is journalled a lever 35 having arms 36 and 37 extending in opposite directions from the crank pin or pivot 34. The lever arms 36 have a roller 38 journalled between their outer ends, and a cam or eccentric 39 is rigidly mounted on the countershaft 15 in position to be engaged by the said roller. The lever arm 37 has an actuating rod 40 pivotally secured to it as at 41, which rod extends downwardly and engages the slotted end of the starting lever 27 of the power discharge mechanism 25. A suitable spring 42, secured to the lever arm 37 and to the frame member 10' or other appropriate fixed part of the apparatus may be employed to prevent disengagement of the rod 40 from the starting lever 27, and also to prevent unintentional engagement of the roller 38 with the constantly rotating cam or eccentric 39. A spring 27', secured to the starting lever 27 and to the frame member 10' or other appropriately fixed part of the apparatus, may be employed to keep the starting lever 27 in proper location to contact with the rod 40.

The shaft 32 also carries an actuating arm 45 which is connected to an arm 46 (see Figs. 5 and 6) of a control lever 47 which is pivotally mounted as at 48 in a housing 49 located conveniently with respect to the operator's station, as for example, on the drum shielding or protecting panel 50. The connections between the arms 45 and 46 preferably comprise a well known form of flexible cable, wherein a wire or strand 51 is surrounded by and longitudinally slidably

in a spirally wound metallic sheath or tube 52. Anchoring supports 52' secure the sheath 52 to the frame 10' and the shield 50 against longitudinal movement.

5 The normal positions of the parts above described are those illustrated in Figs. 2 and 3 (and in full lines in Fig. 5) and their mode of operation is as follows:

At the conclusion of the predetermined period 10 of mixing of a batch of concrete in the drum 12, the batch meter 28 gives its signal, whereupon the operator moves the control lever 47 from the full line position shown in Fig. 5 to the broken line position indicated therein, which swings the arm 15 46 upwardly thereby drawing the wire 51 through its sheath or covering 52 and pulling the arm 45 of shaft 32 downwardly. The said shaft is thus partially rotated to swing its crank arm 33, the crank pin 34 and the lever 35 to the broken line position indicated in said Fig. 5, whereby the follower roller 38 is moved to a position to be engaged by the cam or eccentric 39. The countershaft 15 which carries this cam is being constantly rotated at a relatively low speed—say 90 to 100 R. P. M.—and the cam will thus act upon the roller 38 to swing the lever 35 on its pivot 34, raising its arms 36 and depressing its arm 37. This movement, through the rod 40, will depress the starting lever 27 of the power discharge mechanism 25, as shown in Fig. 6, setting it into operation; and through its linkage 24, 23, 22, 21 and 20, the said mechanism will move the chute 16 into its discharge position within the drum in the usual manner. Since

25 the cycle of operation of the mechanism 25 includes automatic stopping of the said mechanism and resetting of its starting lever 27 when the chute reaches its discharge position in the drum, the operator may restore the control lever 47 to its normal full line position as soon as inward movement of the discharge chute has begun.

30 This return of the control lever to normal will of course restore the parts 32, 33, 34, 35, 38 and 45 to normal, with the roller 38 out of range of

35 the constantly rotating eccentric 39. When discharge has been completed, the operator again manipulates the control lever 47 to cause the actuating mechanism 32, 33, 35, 38, 39, 40 to again depress the starting lever 27 whereupon the power

40 discharge device 25 will return the chute to its inoperative position of Fig. 1, and then stop and reset its lever 27. Crank arm 33 is of such length as to have the same placed at substantially 90 degrees to lever 36 when the operator moves control lever 47 to the broken line position as shown in Fig. 5 so that the reacting force from starting the power discharge may be transmitted to bearing sleeve 31, rather than to the operator through lever 47, which would happen should the crank

45 arm be of greater length.

The interlock between the batch meter and control mechanism, referred to above, is indicated in Fig. 1, and shown more in detail, although rather diagrammatically, in Figs. 5 and

50 6. The batch meter 28 may be of any appropriate type, such for example as that disclosed in U. S. Patent 2,018,964 granted October 29, 1935, on an application filed by Rudolph F. Lindow.

Briefly, such a batch meter is provided with a power-driven shaft 60 which carries a control disk 61 having a recess 62 in its periphery. A dog 63 is carried by a control shaft 64 which also carries a starting lever 65, and the said dog is provided with a toe 66 which is held engaged in

55 the notch 62 by spring 68 when the meter is

60 6. The batch meter 28 may be of any appropriate type, such for example as that disclosed in U. S. Patent 2,018,964 granted October 29, 1935, on an application filed by Rudolph F. Lindow.

Briefly, such a batch meter is provided with a power-driven shaft 60 which carries a control disk 61 having a recess 62 in its periphery. A dog 63 is carried by a control shaft 64 which also carries a starting lever 65, and the said dog is provided with a toe 66 which is held engaged in

65 6. The batch meter 28 may be of any appropriate type, such for example as that disclosed in U. S. Patent 2,018,964 granted October 29, 1935, on an application filed by Rudolph F. Lindow.

Briefly, such a batch meter is provided with a power-driven shaft 60 which carries a control disk 61 having a recess 62 in its periphery. A dog 63 is carried by a control shaft 64 which also carries a starting lever 65, and the said dog is provided with a toe 66 which is held engaged in

stopped (Fig. 6) and which rides upon the periphery of the disk 61 when the meter is timing an operation (Fig. 5). The length of time required for disc 61 to make one revolution determines the mixing period and the speed at which disc 61 revolves is controlled by means described in said patent.

The interlock mechanism comprises a cam disk 70 mounted on the batch meter shaft 60 and having a projection 71. A bell crank lever 72 is pivoted as at 73 and one of its arms 74 carries a roller 75 which is resiliently held against the periphery of the cam disk 70 by spring 72, and rides thereupon. The other arm 76 of the bell crank has connected to it as at 77 one end of a wire 78 which is surrounded by and slidable in a sheath or covering 79; these elements constituting a flexible cable similar to the elements 51, 52 described above. This cable extends from the batch meter to the control lever housing 49 with the end of the sheath 79 being suitably anchored thereat, as indicated at 80, so that the end 78' of the wire 78 may be projected into and withdrawn from the path of the arm 46 of the control lever. The sheath 79 is secured by a clip 82 to an arm 83 carried by the batch meter dog 63, and may furthermore be anchored as at 81 to the frame 10 adjacent the batch meter.

The full line positions shown in Fig. 5 are those which the respective parts occupy say five seconds before the end of the batch meter cycle, it being noted that the end 78' of the wire 78 overlies the end of the control lever arm 46, thereby locking the said lever against operation to initiate movement of the chute 16 to discharging position. Continued rotation of the batch meter shaft 60 and its disks 61 and 70 brings these parts to the broken line positions indicated in Fig. 5 say a few seconds before the batch meter stops, whereby the cam projection 71 on disk 70 will have rocked the bell crank lever 72 in a counterclockwise direction, pulling the wire 78 through its sheath 79 and withdrawing the end 78' from the path of control lever arm 46. The operator thereupon moves the control lever 41 to its broken line position, thus starting the power discharge mechanism 25 as above described, and the chute 16 thus may be moved at least partially to its discharging position by the time the batch meter reaches the end of its cycle and stops.

The parts will now be in the positions indicated in full lines in Fig. 6. Spring 83' will have caused the toe 66 of the dog 63 to enter the notch 62 of the batch meter control disk 61, thereby locking the batch meter against further operation until the said toe is withdrawn from the notch through actuation of the starting lever 65 to begin a new cycle. The cam projection 71 will have moved from beneath the roller 75, permitting spring 72' to return the bell crank lever 72 to its original position. This return movement of lever 72 will push upon the wire 78, but since this movement is coincident with and in the same direction as the movement of the dog 63 to locking position, and since the cable sheath 79 is anchored to the arm 83 of the said dog, there will be no relative movement of the wire within the sheath, but instead the cable will sag or buckle between the anchors 81 and 82, as shown in full lines in Fig. 6, and the end 78' of the wire will not be projected into the path of the arm 46. The control lever 41 is thus free to be returned to its normal full line position of Fig. 5, and to be

again manipulated at conclusion of the discharge to set the power discharge device 25 into operation again to withdraw the chute from the drum, as above explained.

5 The interlock will again become effective only when the batch meter 28 is re-started to time a new mixing period. That is to say, when the batch meter starting lever 65 is moved counterclockwise to lift the toe 66 of the dog 63 out of the recess 62 of the locking disk 61, the said dog with its arm 83 will be swung back to the broken line position of Fig. 6. The effect of this will be to straighten out the sag or buckle in the cable 78, 79 between the clips 81 and 82, as indicated in broken lines in Fig. 6, and since the end of the wire 78 which is attached to the arm 76 of lever 72 can not move, relative movement between the wire and its sheath 79 will occur in that portion of the cable between the anchors 81 and 82 with the result that the end 78' of the wire will again be projected into the path of the arm 46 of the control lever, as also indicated in broken lines in Fig. 6. The control lever thus will be again locked against manipulation until the parts again reach the Fig. 5 positions, when the operations above described will be repeated.

10 While one form of the invention has been illustrated and described, it will be readily understood that those skilled in the art may vary the details of construction as well as the precise arrangement of parts, without departing from the spirit of the invention, and therefore it is not wished to be limited to the above disclosure except as may be required by the claims.

35 What is claimed is:

1. In actuating mechanism for a concrete mixer instrumentality, a power driven cam; a rock shaft mounted adjacent said cam, provided with a crank arm; a lever pivotally mounted on said crank arm, having a follower for engagement with said cam; connections between said lever and the instrumentality to be controlled; and manually operable means for rocking said shaft to move the follower into and out of position to be engaged by the cam.

40 2. Mechanism for governing actuation of a control element of a concrete mixer during the timing of a function of the machine: said mechanism comprising a device for timing said function; means engageable with said control element at the beginning of a cycle of said timing device, whereby to prevent actuation of said element; and means operable by the timing device at a predetermined interval prior to the completion of its timing cycle, to disengage the first named means from the control element, whereby the latter may then be actuated.

45 3. Mechanism for governing actuation of a movable control element of a concrete mixer during a mixing period of the machine: said mechanism comprising a device for timing said mixing period; a member movable into and out of the path of said control element; means for moving said member into the path of the control element simultaneously with the initiation of a timing cycle of said device, whereby actuation of the element may be prevented; and means operable by the timing device to withdraw the member from the path of the control element at a predetermined interval prior to the completion of the timing cycle.

50 4. Mechanism for governing actuation of a movable control element of a concrete mixer dur-

ing a mixing period of the machine; said mechanism comprising a device for timing said mixing period, said device having a starting lever; a member movable to engage and disengage said control element; connections between said member and starting lever whereby the member may be moved to engage the control element simultaneously with the beginning of a timing cycle of the timing device and thus prevent actuation of the control element; and means operable by the timing device just prior to the completion of its cycle to disengage the member from the control element, whereby the latter may then be actuated.

5. Mechanism for governing actuation of a movable control element of a concrete mixer during a mixing period of the machine; said mechanism comprising a device for timing said mixing period, said device having a starting lever; a member movable to engage and disengage said control element; lost motion connections between said member and starting lever whereby the member may be moved to engage the control element simultaneously with the initiation of a cycle of the timing device and thus prevent actuation of the control element; and cam controlled means operable by the timing device at a predetermined interval prior to the completion of its cycle to disengage the member from the control element, whereby to permit actuation of the latter.

6. Mechanism for governing actuation of a movable control element of a concrete mixer during the timing of a function of the machine: said mechanism comprising a device for timing said function, said device having means for starting it into operation; a flexible cable member extending from the timing device and having a portion projectible into a position to be engaged by the control element whereby to prevent actuation of the latter; connections between said cable and the starting means of the timing device whereby the cable member may be projected into said element-engaging position simultaneously with the initiation of a cycle of the timing device;

and means operable by said device for withdrawing the cable member from said element-engaging position toward the end of the timing cycle.

7. Mechanism for governing actuation of a movable control element of a concrete mixer during the timing of a function of the machine: said mechanism comprising a device for timing said function, said device having means for starting it into operation; a flexible cable member extending from the timing device and having a portion movable into engagement with the control element to prevent actuation of the latter; lost motion connections between said cable member and the starting means of the timing device whereby the member may be moved to engage the control element at the beginning of a cycle of the timing device; and cam actuated means connected to the cable member and operable by the timing device at a predetermined interval prior to the end of its timing cycle to withdraw the cable member from engagement with the control element.

8. Mechanism for governing actuation of a movable control element of a concrete mixer during the timing of a function of the machine: said mechanism comprising a device for timing said function, said device being provided with means for starting it into operation; a flexible cable member extending from the timing device and having a portion projectible into the path of said control element whereby to prevent actuation of the latter; a sheath enclosing and slidably accommodating said cable member, a portion of said sheath spaced from the timing device being anchored against movement; connections between the sheath and starting means of the timing device whereby the cable member may be moved into the path of the control element at the beginning of a cycle of the timing device; and means connected to the cable member and operable by the timing device at a predetermined interval prior to the completion of its cycle to withdraw the cable member from the path of the control element.

45 ANDREW McMILLAN.
